ATTORNEY.

UNITED STATES PATENT OFFICE.

ALBERT A. BUSH, OF AKRON, OHIO, ASSIGNOR TO THE OLDFIELD TIRE COMPANY, OF AKRON, OHIO, A CORPORATION OF OHIO.

DESIGN FOR A TIRE TREAD.

60,443.

Specification for Design. Patented Feb. 21, 1922.

Application filed July 18, 1921. Serial No. 485,750. Term of patent 14 years.

To all whom it may concern:

Be it known that I, ALBERT A. BUSH, a citizen of the United States, residing at Akron, in the county of Summit and State of Ohio, have invented a new, original, and ornamental Design for Tire Treads, of which the following is a specification, reference being had to the accompanying drawing, forming a part thereof:

In the drawings Fig. 1 is a plan view of the tire showing my new design.

Fig. 2 is a section on the line 2—2 of Fig. 1.

I claim:

The ornamental design for a tire tread as shown.

ALBERT A. BUSH.
